UNITED STATES PATENT OFFICE.

ARTHUR J. HOWARD, OF MALDEN, MASSACHUSETTS, ASSIGNOR TO THE
WIRE GRIP FASTENING COMPANY, OF CHICAGO, ILLINOIS.

DESIGN FOR A NAIL OR SLUG.

SPECIFICATION forming part of Design No. 24,763, dated October 15, 1895.

Application filed September 16, 1895. Serial No. 562,723. Term of patent 14 years.

To all whom it may concern:

Be it known that I, ARTHUR J. HOWARD, of Malden, in the county of Middlesex and State of Massachusetts, have invented and produced 5 a certain new and useful Design for a Nail or Slug, of which the following is a specification, reference being had to the accompanying drawings, forming a part thereof.

Figure 1 is an isometric view of a nail or 10 slug, showing my design; and Fig. 2 is an end view thereof.

My design relates to nails or slugs for ornamenting the heels of boots or shoes.

The leading feature of my design for a nail 15 or slug consists in two longitudinal depressions formed in each of the opposite sides of the body of a nail or slug, forming a central cylindrical portion separated from two oppositely-located triangular portions by narrow 20 necks.

The body of the nail or slug has formed therein on each side two longitudinal depressions $a a'$, forming two comparatively narrow or thin necks $a^2 a^3$ between a larger cylindrical portion a^4 and two oppositely-located triangular prisms $a^5 a^6$, the prisms being symmetrically located with respect to the cylindrical portion a^4 , with their bases forming the longitudinal edges of the nail or slug. 25

I claim—

The design for a nail or slug, substantially as set forth. 30

In testimony whereof I have signed my name to this specification in the presence of two subscribing witnesses.

ARTHUR J. HOWARD.

Witnesses:

JOHN C. EDWARDS,
ALEX. C. PROUDFIT.
